BANANA KNIFE

Filed Dec. 7, 1931

FIG. 1

FIG. 3

Joseph A. Weigel

INVENTOR

UNITED STATES PATENT OFFICE

JOSEPH A. WEIGEL, OF LA CROSSE, WISCONSIN

DESIGN FOR A BANANA KNIFE

Application filed December 7, 1931. Serial No. 42,158. Term of patent 7 years.

To all whom it may concern:

Be it known that I, JOSEPH A. WEIGEL, a citizen of the United States, residing at La Crosse, in the county of La Crosse and State of Wisconsin, have invented a new, original, and ornamental Design for a Banana Knife, of which the following is a specification, reference being had to the accompanying drawing, forming part thereof.

I claim:

The ornamental design for a banana knife as shown.

JOSEPH A. WEIGEL.
